Inventor:

William Rutan,
by his attorney,
Charles R. Seale.

UNITED STATES PATENT OFFICE.

WILLIAM RUTAN, OF NEW YORK, N. Y., ASSIGNOR TO GILLIS & GEOGHEGAN, OF NEW YORK, N. Y., A FIRM.

CABLE-HOOK.

1,333,038.

Specification of Letters Patent. Patented Mar. 9, 1920.

Application filed September 23, 1919. Serial No. 325,801.

To all whom it may concern:

Be it known that I, WILLIAM RUTAN, a citizen of the United States, residing in the city of New York, borough of Queens, in 5 the county of Queens and State of New York, have invented a certain new and useful Improvement in Cable-Hooks, of which the following is a specification.

The invention relates to hooks intended 10 for attachment to the ends of wire cables employed in hoisting operations, and the object of the invention is to provide a hook having the required strength and form which may be economically manufactured 15 and to which the cable may be easily and reliably secured.

The invention consists in certain details 20 of construction by which the above objects are attained, to be hereinafter described and claimed.

The accompanying drawings form a part of this specification and show the invention as it has been carried out in practice.

Figure 1 is a side elevation of the improved hook, showing in dotted lines the cable-end attached thereto.

Fig. 2 is a corresponding plan view.

Fig. 3 is a front elevation with a portion of the hook-horn broken away to show the 30 body and clamp.

Fig. 4 is a horizontal section, taken on the line 4—4 in Fig. 1, showing the body of the hook and its clamp from below, as indicated by the arrows in such figure.

Similar letters of reference indicate the same parts in all the figures.

The improved hook is in two main parts, one comprising the body A and horn B, and the other a clamp C adapted to be joined to 40 the body by bolts D extending through the latter and the clamp.

The body A and horn B are formed integrally, preferably as a drop-forging, the horn extending downwardly from the heavy 45 rear portion of the body having a cross-sectional area equal to or exceeding the root of the horn B so that the full strength of the horn and body is maintained throughout both.

From the body A extends laterally a vertical flange or cheek A¹ having on its inner 50 face two grooves of semicircular section with a rib or boss A² between them, the latter having its lower end rounded. The boss 55 A² tapers toward the upper end and termi-

nates flush with the upper face of the body and cheek. The rounded lower end terminates a short distance above the lower face of the body and cheek, as indicated by the dotted lines in Figs. 1 and 3.

The line of junction between the cheek A¹ and body A is inclined or beveled as at a, see Figs. 1 and 4, and the body and cheek are preferably tapered upwardly for symmetry and economy of metal. It will be noted that 65 the plane of the beveled face a is outside the cylindrical root of the horn B so that the strength of both body and horn is not impaired.

The clamp C is the counterpart of the 70 cheek A¹ and has similar grooves with a boss C¹ between them, and an inclined or beveled face c matching to the bevel a of the cheek. It is also tapered vertically to correspond in appearance to the body A and cheek A¹ as 75 shown.

Both the cheek and clamp are bored transversely through the bosses A² and C¹ to receive bolts D located one above the other and having nuts D¹ by which the 80 clamp and cheek are drawn together upon a sharp bight of the cable M lying in the grooves and partially inclosing the bosses. The cable is thus firmly gripped and joined to the hook, and is held reliably without 85 requiring soldering or alteration of the cable-end.

By avoiding reentering angles in the parts, both the body and its horn, and the clamp, may be readily formed by the drop-forging process. By making the grooves of such size as to receive the cable snugly therein, with the bend around the lower ends of the bosses as sharp as practicable, all danger of accidental separation is eliminated when the clamp is tightened. The open recess below the bosses permits the cable to be easily threaded into the grooves and adjusted while the clamp is in position prior to tightening.

It will be noted that the boss A² on the cheek A¹ extends beyond the center line, see Figs. 2 and 4, and that the boss C¹ is of less thickness; this construction is preferred for the reason that the strain on the cable in 105 sustaining the load is thus received mainly by the cheek A¹ and transferred directly to the body A, instead of by the clamp and through the bolts D.

The form of hook shown is designed more 110

particularly for service in hoisting ash-cans and other receptacles provided with bails or the like, but it will be understood that the horn and other parts may be shaped as required for other purposes, and other modifications made in the forms and proportions as may be found necessary or desirable in adapting the invention to various uses.

I claim:

10. 1. The cable hook described, comprising a body having a cheek, a horn depending from said body and integral therewith, grooves on the inner face of said cheek and a boss between such grooves, in combination with a clamp having a corresponding boss and grooves on its inner face, adapted to apply against said cheek, said body and clamp having offset contacting faces and means for drawing said clamp and cheek together upon the bight of a cable received in such grooves.
15. 2. The cable hook described, comprising a body having a cheek, a horn depending from said body, a beveled face on the latter extending to said cheek, grooves on the
20. 25. inner face of said cheek, and a boss between such grooves, in combination with a clamp having a corresponding beveled face, and a boss and grooves on its inner face adapted to apply against said cheek, the boss on said cheek being of greater thickness than the boss on said clamp, and bolts extending through said bosses for drawing said clamp and cheek together upon the bight of a cable received in such grooves.

inner face of said cheek and a boss between such grooves, in combination with a clamp having a corresponding beveled face, and a boss and grooves on its inner face adapted to apply against said cheek, and bolts extending through said bosses for drawing said clamp and cheek together upon the bight of a cable received in such grooves.

3. The cable hook described, comprising a body having a cheek, a horn depending from said body, a beveled face on the latter extending to said cheek, grooves on the inner face of said cheek and a boss between such grooves, in combination with a clamp having a corresponding beveled face, and a boss and grooves on its inner face adapted to apply against said cheek, the boss on said cheek being of greater thickness than the boss on said clamp, and bolts extending through said bosses for drawing said clamp and cheek together upon the bight of a cable received in such grooves:

In testimony that I claim the invention above set forth I affix my signature.

WILLIAM RUTAN.
